UNITED STATES PATENT OFFICE.

CHARLES ROCKNELL CLARK, OF PLAINVILLE, CONNECTICUT.

DESIGN FOR A WIND-SHIELD.

44,191.

Specification for Design. Patented June 17, 1913.

Application filed April 14, 1913. Serial No. 761,065. Term of patent 14 years.

To all whom it may concern:

Be it known that I, CHARLES R. CLARK, a citizen of the United States of America, and residing at Plainville, in the county of Hartford and State of Connecticut, have invented a new, original, and ornamental Design for Wind-Shields, of which the following is a specification.

The figure is a vertical projection of a wind shield, showing my new design.

I claim:

The ornamental design for a wind shield, as shown.

CHAS. ROCKNELL CLARK.

Witnesses:

HAROLD F. RYDER,
MARSHALL P. RYDER.

Copies of this patent may be obtained for five cents each, by addressing the "Commissioner of Patents, Washington, D. C."

Correction in Design Letters Patent No. 44,191.

It is hereby certified that the name of the patentee in Letters Patent No. 44,191, granted June 17, 1913, for a design for a "Wind-Shield," was erroneously written and printed "Charles Rocknell Clark," whereas said name should have been written and printed *Charles Rockwell Clark*; and that the said Letters Patent should be read with this correction therein that the same may conform to the record of the case in the Patent Office.

Signed and sealed this 8th day of July, A. D., 1913.
